TUBE PASTE DISPENSER

Arthur B. Chatelain, Los Angeles, Calif., assignor of one-half to Ulrich Fischer, Los Angeles, Calif.

Application September 27, 1933, Serial No. 691,131

8 Claims. (Cl. 221—60)

My invention relates to a device for dispensing paste from tubes by compressing the tubes to cause the exuding of the paste from one end of the tube.

5 An object of my invention is the construction of a simple appliance by which a tube containing paste may be squeezed between two rolls and the paste thus caused to exude from one end of the tube.

10 A further and more detailed object of my invention is to grip the closed end of a paste-containing tube by one roller and to provide means for rotating the roller to coil the collapsed tube on the roller and in the collapsing of the tube 15 to force the sides of the tube together by a co-operating roller co-acting with the winding roller, which latter may be called a pressure roller.

Thus, a feature of my invention is an appliance having a pair of parallel rollers, one of 20 which is provided with a kerf or equivalent device for engaging the closed end of a tube containing paste—such roller may be designated as a winding roller—whereby the tube after being collapsed may be wound in a spiral winding on the winding roller. The collapsing of the tube 25 is caused by a pressure exerted on the tube as it passes between the winding and the pressure rollers and thus the tube may be substantially completely emptied of its contents.

30 A further object of my invention is providing a resilient mounting for one or both of the rollers and, preferably, I mount the pressure roller in a resilient manner in order to accommodate the increased thickness of the tube wrapped on 35 the winding roller as the tube is collapsed.

A further detailed feature in the construction of the resilient mounting for the pressure roller is providing this with a flexible shaft, which shaft may be connected centrally to the pressure roller and have bearings at opposite ends 40 or may have a loose fitting at its opposite ends and have the pressure roller rotate on the central part of the shaft.

45 A further detailed object of my invention is mounting the rollers on a suitable bracket which may be attached to a wall and providing a suspension means for tooth brushes whereby the appliance forms a convenient device for dispensing tooth paste. For suspending the tooth brushes 50 I preferably utilize a hinged cover forming a protector for the winding and pressure rollers and this cover has openings to receive the handles of the tooth brushes.

55 My invention is illustrated in the accompanying drawing, in which:

Fig. 1 is a front elevation taken in the direction of the arrow 1 of Fig. 2.

Fig. 2 is an end elevation taken in the direction of the arrow 2 of Fig. 1.

Fig. 3 is a plan taken in the direction of the arrow 3 of Fig. 1 or 2.

Fig. 4 is a vertical section on the line 4—4 of Fig. 3 in the direction of the arrows.

Fig. 5 is a partial horizontal section on the line 5—5 of Fig. 4 in the direction of the arrows. 10

In constructing my invention I preferably employ a bracket 11 which is illustrated as having a back plate 12 for securing to a wall and two side arms 13 which project at right angles to the back plate. The arms are each provided 15 with a large sized opening 14 and in the pair of openings formed in the two arms there is journaled the winding roller 15. This roller is illustrated as hollow or tubular. It is provided at one end of the winding surface 16 with a flange 17. 20 There is a shoulder 18 at the opposite end of the winding surface and between the arms of the bracket, the shoulder, and the flange there are two washers 19.

The winding roller has a neck portion 20 with 25 a large knob 21 at the end. This knob is provided with a knurled surface 22 to facilitate gripping with the fingers and rotating the roller. This winding roller 15 is provided with a longitudinal kerf 23.

A pressure roller designated 24 is mounted in the bracket parallel to the winding roller and is illustrated as having a shaft 25 with its opposite ends mounted in openings 26, one in each bracket arm. The pressure roller has a cylindrical surface structure 27 and is illustrated as having a central hub 28. Suitable retaining devices, such as an upset end 29, retain the shaft 25 from pulling out of the openings in the bracket arms. 35

The operation of my device so far described is 40 as follows: As above mentioned, the bracket may be secured to a wall and the axes of the two rollers are then on the same horizontal plane. The winding roller may be rotated so that the closed end of a collapsible paste tube may be inserted 45 through the kerf with the end projecting into the interior of the hollow winding roller, as indicated at 30, in Fig. 4. The knob may then be rotated with the fingers in the direction of the arrows 31, which action pulls the tube upwardly between 50 the winding roller 15 and the pressure roller 24. This action suspends the tube with the open end downwardly and in pulling the tube upwardly compresses the walls of the tube together, thus 55 expelling the paste from the tube.

As the tube coils or winds on the winding roller it is necessary to increase the space between the pressure and the winding roller and this is accomplished in my invention by utilizing a resilient mounting for the pressure roller, which mounting is illustrated as having the flexible shaft 25, which shaft can bend sufficiently to accommodate the increased thickness of the tube wound on the winding roller as the tube is increasingly collapsed.

A further feature of my invention comprises the employment of a combination cover and tooth brush support 32. This cover is illustrated as being constructed of a plate 33 hinged at 34 to the upper end of the back plate 12. The marginal edges 35 of the plate engage the upper edge of each of the arms 13 of the bracket, and the outer end 36 depends slightly below the winding roller, as indicated in Fig. 4. This cover plate is provided with a plurality of perforations 37 through which may be extended the handle 38 of a tooth brush designated at 39. The upper portion 40 of the brush engages the plate and holds the tooth brush upright with the brush 25 above the plate and the handle extending downwardly parallel to the collapsible tube.

One of the features in forming the winding roller 15 hollow and open at both ends is that this facilitates inspection as to the proper fitting of 30 the end 30 of the collapsible tube when inserted through the slot or kerf 23 of this roller.

Another important feature of my invention is the use of a flexible axle or shaft 25 for the pressure roller and that this pressure roller has 35 its bearing on the shaft at a central hub 28, thus allowing the shaft to flex while the pressure roller recedes from the roller due to the increased thickness of the collapsed tube on the winding roller. This affords a simple structure for developing a 40 sufficient pressure to squeeze the contents out of the open end of the collapsible tube.

Various changes may be made in the details of construction without departing from the spirit or scope of the invention as defined by the 45 appended claims.

I claim:

1. A paste dispenser comprising a supporting bracket, a winding roller and a pressure roller mounted parallel in said bracket, the winding roller having a longitudinal slot for insertion of the closed end of a collapsible tube, the opposite end of the tube having an opening, said rollers being positioned to suspend the tube with the opening downwardly, means to rotate the winding roller to collapse the tube between the two rollers and to wind the collapsed tube on the winding roller, the pressure roller having a flexible shaft, said shaft being adapted to bend to vary the spacing between the two rollers.

2. A paste dispenser comprising, in combination, a bracket having a pair of side arms with means for attaching said arms to a wall, a hollow winding roller journaled in said arms and having an enlarged knob for rotating said roller, said roller having a longitudinal slot for insertion of the closed end of a collapsible tube, a flexible shaft having its opposite ends mounted in the side arms, a pressure roller journaled on said shaft, the pressure and winding rollers being parallel and positioned to suspend a tube

downwardly when collapsed between the two rollers, the said shaft being adapted to flex to increase the distance between the two rollers as the collapsed tube is wound on the winding roller.

3. A paste dispenser comprising, in combination, a supporting structure, a rotatable winding roller journaled therein, said winding roller having a longitudinal slot for insertion of the closed end of a collapsible tube, a pressure roller having a flexible shaft, said shaft being mounted in the supporting structure substantially parallel to said winding roller, the said shaft being adapted to flex when a collapsed tube is wound on the winding roller.

4. A paste dispenser comprising, in combination, a supporting structure, a winding roller journaled therein, means to rotate said roller, a flexible shaft mounted in the supporting structure, a pressure roller journaled on said supporting structure, said rollers being parallel, means on one of said rollers to engage an end of a collapsible tube, the rotation of the winding roller winding the collapsible tube thereon, the said shaft flexing to increase the spacing between the two rollers.

5. A paste dispenser as claimed in claim 4, the 25 said pressure roller having a central hub, said hub being journaled on the said flexible shaft.

6. A paste dispenser comprising, in combination, a supporting structure, a tubular winding roller open at both ends journaled on said supporting structure, means at one end of said roller for rotating the same, said roller having a slot for insertion of the end of a collapsible tube, a pressure roller journaled on a flexible shaft, the ends of the shaft being mounted in the supporting structure, and the pressure roller being parallel to the winding roller, said shaft flexing and allowing displacement of the pressure roller from the winding roller when a tube is wound on the winding roller.

7. A paste dispenser as claimed in claim 6, the ends of the flexible shaft being mounted in opposite sides of the supporting structure, the pressure roller being hollow except for a central hub, and said central hub engaging the center portion of 45 the flexible shaft whereby said shaft may be bent between the hub and its opposite supported ends.

8. A paste dispenser comprising, in combination, a bracket having a pair of side arms, said arms being adapted to extend horizontally from 50 a vertical wall, each of said arms having an enlarged opening, a tubular winding roller journaled in said openings, said roller having a neck with a knob on the end for rotating the winding roller, said winding roller having a longitudinal slot between said arms for insertion of the end of a 55 collapsible tube from the outside to the inside of the winding roller, said winding roller being open at both ends, a flexible shaft having its ends mounted in the side arms, and a hollow pressure 60 roller having a central hub with the hub mounted on the central portion of the flexible shaft, said rollers being parallel and having their axes in the same horizontal plane, said flexible shaft being adapted to flex between the hub and its ends when 65 the pressure roller is displaced from the winding roller due to increased thicknesses of the collapsible tube being coiled on the winding roller.
